Attorney.

UNITED STATES PATENT OFFICE

MARCO H. HELLMAN, OF LOS ANGELES, CALIFORNIA

SHIPPING AND DISPLAY CASE FOR BRIDLES

Application filed December 10, 1927. Serial No. 239,070.

This invention relates to cases for transporting bridles, and the primary object thereof is to provide such a case which shall serve not only for shipping a plurality of bridles but also for retaining them in such position that they may also be exhibited while remaining in the container. A further object is to so dispose the parts that it will be difficult for the bridles to be dislodged from their supports during shipping.

Briefly stated, the invention resides in a container provided with a movable closure and having therein a support in the form of an arm or the like which has appreciable width to receive the upper portion of the head strap and which has a slot to receive the front or forehead strap. Preferably each support is adapted to receive a plurality of bridles. Preferably also the forward end of each support is provided with guards to prevent the bridles from slipping off.

In the accompanying drawing, wherein one embodiment of the invention is disclosed by way of illustration, a perspective view of a preferred form is shown.

This shipping and display case has end walls 10, a back 12, a hinged top 14, a front wall 15 to which a drop or flap 16 is hinged at 18 to complete the front wall, and a plurality of bridle supporting arms 20. Each of these arms 20 has its rear end secured to the back wall 12, each arm projecting horizontally forward as seen and being provided with a vertically disposed slot 22 which extends a considerable distance back into the arm. To the bifurcations of these supporting arms pairs of guard fingers 24 are secured, the upper ends of the fingers projecting above the arms as seen to prevent the bridles from slipping forward far enough to fall off the supports. The supports 20 are of substantial width as shown and are curved at 25 whereby a suitable seat is provided for the upper portion of the head strap 26 of each bridle placed thereon, while the front strap or forehead piece 28 passes between the bifurcations and lies in the slot 22, and the transverse strap 30 passes back under the bifurcations.

In this manner several bridles may be mounted upon each supporting arm 20, the

front straps 28 entering slots 22 and positioning the bridles against lateral shifting. With the top 14 in elevated position and the front 16 down as shown, the bridles are conveniently displayed without removal from the supports. For shipping, the flap 16 is merely elevated and the top 14 lowered so that the lip 14' thereof will enter the longitudinal rabbet 16' in the flap. Dislodgment of the bridles is at least partially prevented by engagement of the transverse straps 30 of the rear bridles under the respective arms 20.

Thus a plurality of bridles is both shipped and exhibited on the same supports, a mere swinging movement of the closure members converting the device from a display case to a shipping container. Since various modifications of the device may be made within the scope of the claims hereunto appended, the preferred form above described is not to be considered as limiting in any sense.

I claim:

1. A bridle case comprising a container, a bridle support mounted therein and projecting horizontally, said support being bifurcated vertically, and guards projecting upward from the outer end of the support to prevent the bridles from slipping therefrom.

2. A shipping and display case for animal bridles comprising a container having an opening and closure therefor, and a plurality of bridle supporting posts each having a central vertical opening for the reception of the forehead straps of animal bridles when mounted on said posts secured to one of the vertical walls of said container and extending outwardly therefrom, said posts being spaced apart and disposed in horizontal alignment.

In testimony whereof I affix my signature.

MARCO H. HELLMAN.
